UNITED STATES PATENT OFFICE.

HERMAN IHLENBURG, OF PHILADELPHIA, PENNSYLVANIA, ASSIGNOR TO THE
MACKELLAR, SMITHS & JORDAN COMPANY, OF SAME PLACE.

DESIGN FOR A FONT OF PRINTING-TYPE.

SPECIFICATION forming part of Design No. 20,198, dated October 14, 1890.

Application filed July 21, 1890. Serial No. 359,447. Term of patent 7 years.

To all whom it may concern:

Be it known that I, HERMAN IHLENBURG, a citizen of the United States, and a resident of Philadelphia, Pennsylvania, have invented a new and original Design for a Font of Printing-Type, of which the following is a specification.

My design for a font of type is clearly illustrated in the accompanying typographical impression.

The font of type is of an ornamental character, and represents letters made by a pen, free hand, the lines of the type being undulating and uneven throughout. The main lines of the upper-case type are undulating at certain parts, giving an uneven appearance, and each letter has one or more of its ends curled,

as in the form of a scroll shown, and the other free ends of the letters being either finished by a cross-bar or ending in a waved line.

The letters of the lower case are in keeping with the letters of the upper case, and the figures are in keeping with the letters.

I claim—

The design for a font of type, as clearly described, and shown in the annexed typographical impression.

In testimony whereof I have signed my name to this specification in the presence of two subscribing witnesses.

HERMAN IHLENBURG.
